(57) **CLAIM**

The ornamental design for a drill housing, as shown and described.

DESCRIPTION

FIG. 1 is a first perspective view of a drill housing, according to an embodiment of the invention;

FIG. 2 is a second perspective view of the drill housing of FIG. 1;

FIG. 3 is a first side view of the drill housing of FIG. 1;

FIG. 4 is a second side view of the drill housing of FIG. 1;

FIG. 5 is a first end view of the drill housing of FIG. 1;

FIG. 6 is a second end view of the drill housing of FIG. 1;

FIG. 7 is a top view of the drill housing of FIG. 1; and,

FIG. 8 is a bottom view of the drill housing of FIG. 1.

The broken lines are for the purpose of illustrating portions of the drill housing and form no part of the claimed design.

1 Claim, 8 Drawing Sheets
